UNITED STATES PATENT OFFICE

REYNOLD W. PETERSON, OF GALVA, ILLINOIS

ACID JAR

Application filed December 10, 1928. Serial No. 325,004.

This invention relates to a non-splash container for acids and the like, the general object of the invention being to form the container with an enlarged top portion which forms a seat at its junction with the rest of the container and to provide a cover for engaging the seat and a cover for engaging the top part of the enlargement, with means for clamping both covers in closed position, 5 the clamping means for the inner cover being carried by the other cover.

This invention also consists in certain other features of construction and in the combination and arrangement of the several parts, to 15 be hereinafter fully described, illustrated in the accompanying drawing and specifically pointed out in the appended claims.

In describing the invention in detail, reference will be had to the accompanying drawing 20 wherein like characters denote like or corresponding parts throughout the several views, and in which:—

Figure 1 is a vertical sectional view through the device.

25 Figure 2 is a top plan view.

In these views, the numeral 1 indicates the container which is formed with an enlarged upper part 2, a seat or shoulder 3 being formed at the junction of the two parts. A 30 beveled seat 4 is formed at the upper end of the enlargement to receive a cover 5 which is preferably of wood and which has a bushing 6 at its center which is internally screw threaded. A second cover 7 of dome shape 35 is adapted to be placed in the enlarged part of the container and engage the seat 3 and a screw 8 is threaded through the bushing and has its lower end engaging the knob 9 formed on the top of the cover 7 so that when 40 this screw is tightened, the cover 7 is forced against the seat 3. The cover 5 is held in place by a number of clamps A, each of which consists of a plate 10 fastened to the cover 5 and having a slotted projection 11 thereon 45 which extends upwardly and inwardly, and

a hook-shaped member 12 which has a forked inner end, the prongs of which fit over the projection 11, with a pin 13 passing through the prongs and the slot, a set screw 14 passing through a threaded hole in the hook member and engaging the plate 10 so that by tightening this screw, the hook part of member 12 will be forced into clamping engagement with the bead 15 formed around the top of the enlargement 2, thus clamping the cover 5 in place. As the screw is loosened, 50 the pin 13 will pass downwardly through the slot in the projection 11, thus causing the hook part of member 12 to move away from the bead so that the cover 5 can be removed. Suitable handles 16 are connected with the 55 enlarged part of the container.

From the foregoing it will be seen that the two covers are firmly held in place and thus there is no danger of the contents of the 60 container splashing therefrom while the container is being transported from place to place.

It is thought from the foregoing description that the advantages and novel features 65 of the invention will be readily apparent.

It is to be understood that changes may be made in the construction and in the combination and arrangement of the several parts, provided that such changes fall within the 70 scope of the appended claims.

What I claim is:—

1. A device of the class described comprising a container having an enlarged upper part which forms an internal seat at its junction with the lower part, said enlarged part having a beveled seat at its upper end, a cover having a beveled edge engaging the said seat, clamps for clamping the cover to the upper part of the receptacle, a cover within the 80 enlargement and engaging the shoulder and a clamping screw passing through the first cover and engaging the second cover when the screw has been turned to a certain position, for holding the second cover in place. 85 90

2. A container comprising a body part having a beveled seat at its upper end, a cover having a beveled periphery engaging said seat, upwardly and inwardly extending slotted projections on the cover, a hook member associated with each projection, a pin passing through the rear end of each hook member and through the slot in each projection and a set screw passing through each hook member and engaging a part of the cover for forcing the hook part into engagement with a part of the receptacle.

In testimony whereof I affix my signature.
REYNOLD W. PETERSON.
